CLAIM

The ornamental design for a shelf bracket, as shown and described.

DESCRIPTION

FIG. 1 is a front, right, top perspective view of the first embodiment of a shelf bracket, showing my new design; FIG. 2 is a rear, left, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; and, FIG. 8 is a bottom plan view thereof.

The dashed broken lines in the figures are for the purposes of illustrating portions of the shelf bracket and form no part of the claimed design.

The article is shown with a symbolic break in its length. The appearance of any portion of the article between the break lines forms no part of the claimed design.
